UNITED STATES PATENT OFFICE.

GRANT HOLMES, OF DANVILLE, ILLINOIS, ASSIGNOR TO THE MARION STEAM SHOVEL COMPANY, OF MARION, OHIO, A CORPORATION OF OHIO.

BOOM.

Application filed July 30, 1923. Serial No. 654,563.

This invention relates to booms and is designed more particularly for use in connection with power shovels of the revolving type.

One object of the invention is to provide a boom of great strength; and, further, to provide such a boom which will be of relatively light weight as compared with its strength; and which can be produced at a relatively low cost.

Rotary power shovels as constructed in the past have for the most part comprised a rotary frame on which the boom was mounted, the foot of the boom usually resting in a socket or between ears at the front end of the frame and extending upwardly and forwardly at an angle of about forty five degrees. The boom is held in this position by suspension from the point thereof by means of cables or hog rods extending from the boom to a gantry, or A frame, mounted on the revolving frame and braced or stiffened by means of a bridge, which bridge also provides a high point for connecting the cables or hog rods. The boom itself is usually heavier, or of greater size, near the center thereof and the upper and lower sides or edges thereof converge forwardly and rearwardly. The shipper shaft and crowding engine are mounted on this heavier portion of the boom and the dipper handle extends through the boom adjacent to the shipper shaft. When a machine of this character is not working and the dipper is resting on the ground the boom is subject to certain strains, the under side of the boom being under tension and the upper side of the boom being in compression. When the dipper is raised off the ground these strains are proportionately increased, it being understood that in the larger types of shovels these dippers are of large size and even when empty impose a heavy load on the boom. When the dipper is crowded into the face of the bank, upon which it is working, a backward thrust is exerted through the dipper handle and shipper shaft and this thrust serves to reverse the strains imposed upon the boom, the lower side of the boom being placed under compression and the upper side of the boom being placed under tension. After the dipper has finished its cut and the weight of the loaded dipper imposed on the boom the strains are again reversed, bringing the lower side of the boom

under tension and the upper side under compression. It will be understood that in the operation of the shovel this reversal of the strains takes place at frequent intervals and is highly destructive of the boom. As has been stated most booms of this character are heavier adjacent to the shipper shaft, but the portion of the boom between the shipper shaft and the point is subjected to these constantly reversing strains with the result that it is gradually weakened to the breaking point. Further, the swinging of the loaded dipper imposes a very severe twisting strain on the lower or foot portion of the boom, which is smaller in section, usually about one-third of the distance from the foot of the boom to the shipper shaft, and this strain gradually weakens this portion of the boom to the breaking point. These strains are present in all booms of this character but they become more pronounced in the larger size machines and it has been found impractical to increase the size and strength of a boom of this kind sufficiently to overcome the destructive action of the strains upon the boom.

A further object of the invention is to so construct the boom that these reversing strains will be reduced to such a degree that they will not be serious. To accomplish this it is also an object of the invention to provide a boom structure in which the boom will be integral with the rotating frame.

A further object of the invention is to provide such a boom structure which may be built largely of plates, which not only enable it to be produced at a low cost but provide a very large degree of strength in proportion to their weight.

Other objects of the invention will appear as the device is described in detail.

In the accompanying drawings Fig. 1 is a side elevation of a rotary steam shovel embodying my invention; Fig. 2 is a top plan view of the same; Fig. 3 is a section taken on the line 3—3 of Fig. 1; Fig. 4 is a section taken on the line 4—4 of Fig. 1; Fig. 5 is a bottom plan view of the boom structure; Fig. 6 is a longitudinal sectional view of the boom structure and platform; and Fig. 7 is a sectional view taken on the line 7—7 of Fig. 1.

In these drawings I have illustrated one embodiment of my invention and have shown the same as applied to a rotary power

shovel of large size, such as are commonly used for stripping the over-burden from surface deposits of coal and ore. Shovels of this type are of very large size, many of them employing a boom 90 feet in length with a dipper having a capacity of eight cubic yards, and it will be apparent that a very heavy load is imposed upon the boom. Because of the weaknesses which develop in these booms, as above set forth, it has been found impractical to extend the length of the boom or the capacity of the dipper beyond those stated.

The steam shovel here shown comprises a base 1 which is mounted on suitable traction devices, such as trucks 2, and carries a platform 3, which is mounted on the base for rotation about a vertical axis, as shown at 4. This platform carries the power plant and the operating and controlling machinery for the excavating mechanism. In applying my invention to such a shovel I mount on the revolving platform a frame which extends upwardly therefrom and is rigidly secured thereto. Rigidly secured to this frame and preferably formed integral therewith is the boom proper which extends upwardly and forwardly from the frame and which tapers from the frame to the point of the boom. The frame extends lengthwise of the revolving platform and is secured thereto both in front of and in the rear of the axis of rotation and inasmuch as this frame constitutes a part of the boom structure it will be apparent that the boom itself rotates about a vertical axis extending through the lower portion thereof.

The boom structure may be constructed in various ways but I prefer to build the same from metal plates connected together and reinforced by such angles, channel beams and the like as may be necessary. To this end I have, in the present embodiment of my invention, formed the frame portion of the boom structure from two upright plates 5 extending lengthwise of the platform and rigidly secured thereto in any suitable manner, as by means of angles 6. In the present instance, these frame members or plates 5 are triangular in shape and extend for the full length of the platform, the apex of the angle being arranged adjacent to the axis of rotation of the platform so as to provide the highest part of the frame at this point. It will be obvious, however, that the frame members may take various shapes and that it is not essential that they should extend for the full length of the platform. The plates are preferably reinforced or stiffened, as by securing thereto transverse bars or angles 7. Further, the plates are braced and held rigidly in their upright positions by means of brace bars 8, preferably angle bars, rigidly secured at their lower ends to the platform 3

and connected at their upper ends with the upper edges of the respective plates 5 by means of top plates 9 which are rigidly connected both to the brace bars and the frame members and are preferably reinforced with angle irons. If desired, bulkheads 8^a, formed of plates or bars, may be interposed between the reinforcing bars 7 and the brace bars 8 to further stiffen the structure. The frame members or plates 5 are spaced a considerable distance apart and, in the present instance, are spaced short distances from the respective lateral edges of the platform. These plates may, if desired, form a part of the housing 10 within which the power plant and operating mechanism are arranged.

Extending forwardly from the edges of the respective frame members or plates 5 are two forwardly converging plates 11 which are rigidly connected at their rear edges with the forward edges of the respective frame plates, preferably by riveting, so as to form in effect an integral part of the structure. The forward ends of these converging plates are spaced short distances apart, and rigidly connected with the respective forward edges thereof are other plates 12 which extend forwardly and upwardly therefrom, these plates also being secured to the converging plates by means of rivets or the like in such a manner as to form an integral part thereof. The plates 12 are arranged substantially parallel so as to form between them a space through which the dipper handle 13 may extend. The converging plates 11 and the parallel plates 12 are preferably reinforced by transverse angle bars 14 and are braced by upright brace bars or angles 15 spaced therefrom on the outer sides thereof and connected thereto by bottom plates 16 and a top plate 17. Preferably bulkheads 15^a, similar to the bulkheads 8^a, are connected with each pair of bars, 14 and 15, to form very rigid braces for the vertical plates. The top plate 17 is of a width equal to the overall width of the boom and is rigidly secured to the upper edges of both sets of plates, 11 and 12, and to the brace bars 15 and plates 15^a on each side of the boom, thereby uniting these parts in an integral structure. The bottom plates 16 are separate one from the other so as to provide a space between the lower edges of the vertical plates throughout the length of the boom proper. The converging plates 11 are connected one to the other by a transverse plate 18 secured at its lateral edges to the respective converging plates and, in the present instance, arranged in a substantially horizontal position. The rear edge of this plate 18 is turned upwardly, as shown at 19, and is rigidly secured to the forward edges of the frame plates 5, thus tying these frame

plates together and reinforcing the frame structure. A vertical plate 20 extends transversely between the plates 12 adjacent to their points of connection with the plates 11. The top plate 17 is provided near the longitudinal center of the boom with an opening 21 through which the dipper handle 13 extends. Extending downwardly from the rear edge of the opening 21 to the lower edge of the vertical transverse plate 20 is a transverse tie plate 22. Extending forwardly from the forward edge of the opening 21 in an approximately horizontal position is a transverse plate 23, and extending from the forward edge of the transverse plate 23 upwardly is a substantially vertical transverse plate 24. The plates 22, 23 and 24, are rigidly secured at their respective edges to the plates 12 and 20 the plates 22 and 23 are so arranged as to provide an ample space within which the dipper handle may swing. The vertical transverse plate 24 is spaced from the point of the boom a distance sufficient to permit 25 of the mounting of the sheaves between the two plates at the point of the boom. It will be apparent that by assembling the parts in the manner set forth I have provided a unitary boom structure comprising within 30 itself an integral frame and boom. The upper and lower edges of the plates 11 and 12 converge toward the point of the boom so as to give the boom a tapered shape from the frame portion thereof to the point thereof. I prefer that the lower edge of the boom shall constitute a straight line from its point of connection with its frame members to the point thereof. If desired, the upper edge of the boom may also constitute a 35 straight line from the point of the boom to the rear edge of the frame members which, in the present instance, is the rear end of the platform. However, it is not essential that the upper edge of the boom 40 should be straight and it may be given any suitable shape. The top plate 18 converges from the frame members to the forward end or joint of the boom so that the lateral sides of the boom structure as a whole converge forwardly.

It will be apparent that a boom so constructed will have very great strength, and that the plates being arranged on edge will provide a relatively large degree of strength 55 in proportion to their weight. The converging plates extending from the forward edges of the widely separated frame plates to the rear edges of the narrowly separated boom. Plates 12 serve not only to connect the plates 12 of the outer portion of the boom structure with the frame members but also to brace the outer portion of the boom structure against the frame and thus resist the strains imposed thereon by the

swinging of the load. It will be noted that 65 these converging plates 11 and the plate 18 are so arranged that they brace the boom structure at the point where the swinging strains are the greatest. It will be understood, of course, that the load on the rear 70 portion of the revolving frame will be sufficient to counterbalance the forward or boom portion of the structure. Ordinarily the weight of the power plant and other mechanism mounted on the platform will be sufficient for this purpose but obviously additional weight could be provided if necessary. The boom structure as a whole comprises in effect cantilever construction and the underside of the boom will always be 75 so under compression and the upper side thereof will always be under tension, thereby eliminating entirely the reversal of tension and compression on the upper and lower edges of the boom which are so destructive of the old type of boom. Further, in this construction the cross sectional area of the boom increases from the point of the boom to the base or frame portion thereof 80 and this, coupled with the bracing action 90 of the converging plates, 11 and 18, entirely overcomes the strains imposed on the boom by the swinging of the load.

Not only does this boom structure eliminate the destructive strains which were 95 present in the former booms but by so doing it makes it possible to increase both the length of the boom and the capacity of the dipper. Further, the character of the construction is such that the boom may 100 be built and assembled at a relatively low cost, the sheets being easily formed and assembled. Further, the construction is self-supporting, that is, the forwardly and upwardly extending portion of the boom structure is supported by the frame portion 105 thereof without suspending devices of any kind, and I am enabled to do away entirely with the sway cables or hog rods, the suspension cables, the A frame or gantry, the 110 bridge, and many other smaller parts which were essential in the former type of construction, thereby not only further reducing the cost but simplifying the construction of the machine as a whole and greatly 115 reducing the maintenance cost. It will be understood that the crowding engine and its associated parts will be mounted on the upper edge of the boom, together with such other mechanism as may be desirable in 120 the operation of the machine, but as these parts form no part of the invention and would add nothing to the disclosure they have been omitted. The transverse brace plate 18 being arranged in a horizontal position between the converging plates 11, 125 may conveniently be used as a work floor on which repair work may be done on ya-

rious parts of the mechanism carried by the boom without the necessity of lowering these parts to the ground.

When the boom structure is to be erected in the field the frame will be erected on the revolving platform and the outer portion of the structure, or the boom proper, will be erected on blocks in a substantially horizontal position and when assembled the lower rear edge of this portion of the boom will be connected with the forward edges of the frame plates 5, or with the frame 3, by a hinge or pivot pin 27. The boom is provided on its upper edge with a nest of sheaves and a second nest of sheaves 29 is mounted on the upper edges of the frame plates. The hoisting cable from the main hoisting engine is fitted about the sheaves of the two nests and by the application of power to this cable the boom is raised to its elevated position and may then be riveted or bolted in that position, thereby integrally connecting the boom and the rotating frame into a unitary boom structure.

1 will be understood that, particularly in the larger sizes, it will not be practical to form the several plates of single pieces of metal but that each plate will be built up from a plurality of plates of standard size. While I prefer that the several members herein referred to as "plates" shall be in the form of flat plates, in strict meaning of the term, this is not absolutely essential and these members may be of any suitable construction.

While I have shown and described one embodiment of my invention I wish it to be understood that I do not desire to be limited to the details thereof as various modifications may appear to a person skilled in the art.

Having now fully described my invention, what I claim as new and desire to secure by Letters Patent, is:

1. In a machine of the character described, the combination with a revolving platform, of a boom structure having a lower portion comprising side frames mounted on said platform in spaced relation one to the other, extending for substantially the full length of said platform and having their upper edges inclined upwardly and forwardly, said boom structure also having an upwardly and forwardly extending portion, the upper and lower edges of which converge forwardly, the rear end of the last mentioned portion of said boom structure being of a height substantially equal to the height of the forward ends of said side frames and being rigidly secured thereto.

2. In a machine of the character described, the combination with a revolving platform, of a boom structure having a lower portion comprising triangular side plates having their lower edges mounted on said platform

in spaced relation one to the other and extending for substantially the full length thereof, said boom structure also having an upper portion comprising plates spaced one from the other and rigidly connected one to the other, the last mentioned plates being rigidly secured at their lower rear ends to the forward ends of the respective triangular plates and having their upper and lower edges converging forwardly therefrom.

3. In a machine of the character described, a revolving platform, an integral boom structure rigidly secured to and wholly supported by said platform, said boom structure having its upper and lower edges converging from said platform toward the point of the boom, the lower edge of said boom structure terminating adjacent to and being secured to the forward edge of said platform and the upper edge of said boom extending to a point adjacent to the rear edge of said platform.

4. In a machine of the character described, a revolving platform, an integral boom structure rigidly secured to and wholly supported by said platform, said boom structure having straight upper and lower edges converging from said platform toward the point of the boom, the lower edge of said boom structure terminating adjacent to and being secured to the forward edge of said platform and the upper edge of said boom extending to a point adjacent to the rear edge of said platform.

5. In a machine of the character described, a revolving platform, and a self supporting inclined boom structure having the lower end portion thereof resting upon and rigidly secured to said platform and extending lengthwise thereof from a transverse line in front of its axis of rotation to a transverse line in the rear of said axis, the lower edge of said structure terminating adjacent to said platform.

6. An integral boom structure having a lower portion constituting a supporting base, and an upper portion constituting a boom arm, said base comprising side frames rigidly mounted in spaced relation one to the other, said boom arm comprising members spaced one from the other a distance less than the distance between said side frames, rigidly connected one to the other and having forwardly and upwardly converging upper and lower edges, and means for connecting the rear ends of the members of said boom arm with the forward ends of the respective side frames and for bracing said boom arm against said side frames to resist lateral strains on said boom arm.

7. In a machine of the character described, a revolving platform, upright frame members rigidly secured to and extending lengthwise of said platform near the respec-

5 tive lateral edges thereof, connecting members rigidly secured to the forward edges of the respective frame members and converging forwardly therefrom, and an inclined boom arm rigidly secured to the forward edges of said connecting members and supported by said frame members.

8. In a machine of the character described, a revolving platform, upright frame members rigidly secured to and extending lengthwise of said platform near the respective lateral edges thereof, an inclined boom arm comprising substantially parallel members rigidly connected one to the other 10 and spaced apart a distance less than the distance between said frame members, and forwardly converging connecting members each rigidly connected at its respective ends with one of said frame members and one 15 member of said boom arm.

9. In a machine of the character described, a revolving platform, a power plant and operating mechanism mounted on said platform, longitudinally arranged plates 20 rigidly secured to said platform and extending upwardly therefrom on the respective sides of said power plant and operating mechanism, and an elongated structure comprising upright plates rigidly connected one 25 to the other and rigidly secured to and supported wholly by the first mentioned plates.

10. In a machine of the character described, a revolving platform, longitudinally arranged plates rigidly secured to said platform and extending upwardly therefrom and arranged to form portions of the side walls of a housing mounted on said platform, an elongated structure comprising upright plates rigidly secured to and supported wholly by the first mentioned plates. 30

11. In a machine of the character described, a platform, a housing mounted on said platform and comprising metal plates arranged on edge and rigidly secured to said platform, and other plates secured to the edges of the first mentioned plate and extending upwardly and forwardly therefrom to form an elongated structure supported by the first mentioned plates. 40

50 12. In a machine of the character described, a platform, and a unitary boom structure comprising a pair of upright plates rigidly secured at their lower edges to said platform and spaced one from the other, connecting plates secured to the respective upright plates and converging forwardly therefrom, and a pair of elongated plates spaced relatively short distances apart and rigidly secured to the forward edges of said connecting plates.

13. In a machine of the character described, a platform, a pair of upright plates mounted on said platform, and spaced one from the other, a second pair of plates arranged in substantially vertical planes par-

allel one with the other and spaced apart a distance less than the distance between the first mentioned plates, and connecting plates arranged obliquely to the first mentioned plates and rigidly connected with the respective plates of the first mentioned pair and of the second pair of plates, to form a unitary structure. 70

14. In an integral boom structure, a lower revolving frame portion comprising upright plates spaced one from the other, and an outer boom portion comprising vertical plates rigidly secured to the perspective first mentioned plates, said boom portion being supported wholly by said frame portion and said boom portion converging from said frame portion toward the outer end thereof. 75

15. In an integral boom structure a lower frame portion comprising upright frame members, and an outer boom portion comprising substantially parallel vertical plates, and converging vertical plates connecting the respective parallel plates with the corresponding frame members. 80

16. In an integral boom structure a lower frame portion comprising upright plates rigidly mounted in spaced relation one to the other, forwardly converging plates rigidly secured to the forward edges of the respective frame plate, a transverse plate arranged between and extending lengthwise of and rigidly secured at its respective edges to said converging plates, and substantially parallel plates rigidly secured to the forward edges of said converging plates and rigidly connected one to the other. 90

17. In an integral boom structure a lower frame portion comprising upright plates rigidly mounted in spaced relation one to the other, forwardly converging plates rigidly secured to the forward edges of the respective frame plates, a transverse plate arranged between and extending lengthwise of and rigidly secured at its respective edges to said converging plates, and substantially parallel plates rigidly secured to the forward edges of said converging plates, and transverse plates arranged between said parallel plates, rigidly connected at their respective edges thereto and arranged obliquely to the length of said parallel plates. 100

18. In an integral boom structure a lower frame portion comprising upright plates rigidly mounted in spaced relation one to the other, and outer boom portion comprising parallel plates spaced a relatively short distance one from the other, and converging plates to connect the last mentioned parallel plates with the respective frame plates, and a top plate extending across said parallel plates to rigidly connect the same one to the other. 110

19. In an integral boom structure a lower frame portion comprising upright plates rigidly mounted in spaced relation one to the 115

- other, an outer boom portion comprising parallel plates spaced a relatively short distance one from the other, and converging plates to connect the last mentioned parallel plates with the respective frame plates, and a single top plate rigidly secured to the upper edges of said parallel plates and said converging plates.
20. In an integral boom structure a lower frame portion comprising upright plates rigidly mounted in spaced relation one to the other, an outer boom portion comprising parallel plates spaced a relatively short distance apart, and converging plates connecting said parallel plates with said frame plates, top and bottom plates secured respectively to the upper and lower edges of said parallel plates and said frame plates and extending laterally beyond the edges of the respective upright plates, and upright brace bars extending between the respective outer edges of said top and bottom plates.
21. In an integral boom structure a lower frame portion comprising a pair of substantially triangular plates rigidly mounted in upright positions and spaced one from the other, forwardly converging plates rigidly secured at their rear edges to the forward edges of said triangular plates, and parallel plates rigidly secured to the forward edges of said converging plates and spaced a short distance one from the other.
22. In an integral boom structure a lower frame portion comprising a pair of substantially triangular plates rigidly mounted in upright positions and spaced one from the other, forwardly converging plates rigidly secured at their rear edges to the forward edges of said triangular plates, parallel plates rigidly secured to the forward edges of said converging plates and spaced a short distance one from the other, the lower edge of said structure comprising a straight line from the outer end thereof to the forward edges of said triangular plates.
23. In an integral boom structure a lower frame portion comprising a pair of substantially triangular plates rigidly mounted in upright positions and spaced one from the other, forwardly converging plates rigidly secured at their rear edges to the forward edges of said triangular plates, and parallel plates rigidly secured to the forward edges of said converging plates and spaced a short distance one from the other, the upper and lower edges of said converging plates and said parallel plates converging forwardly.

In testimony whereof, I affix my signature hereto.

GRANT HOLMES.
